S. H. HARRISON.
KILN AND FIRE BRICK THEREFOR,
APPLICATION FILED FEB. 24, 1920.

1,374,203.

Patented Apr. 12, 1921.

Attorney.

UNITED STATES PATENT OFFICE.

SIMON HENRY HARRISON, OF EASTON, PENNSYLVANIA, ASSIGNOR OF ONE-HALF TO
S. WARREN HARTWELL, OF EASTON, PENNSYLVANIA.

KILN AND FIRE-BRICK THEREFOR.

1,374,203.

Specification of Letters Patent. Patented Apr. 12, 1921.

Application filed February 24, 1920. Serial No. 360,653.

To all whom it may concern:

Be it known that I, SIMON HENRY HARRISON, usually known as S. HENRY HARRISON, a citizen of the United States, residing at 318 Parsons street, Easton, in the county of Northampton and State of Pennsylvania, have invented a certain new and useful Kiln and Fire-Brick Therefor, of which the following is a specification.

10 My invention relates to fire brick of the character used to line metallic casings and in which there is excessive conduction heat loss through the fire brick to the metallic casing and thence by radiation to the air.

15 The purpose of my invention is to form recesses in the faces of the fire brick, so that there shall be dead air pockets at these points, and so that the contact with the surrounding metallic cylinder shall be limited to the edges of the recesses, limiting these air spaces to the size of a single brick face, or at least to a small area preferably extending circumferentially within the casing. The air in each space is subject 25 throughout to substantially the same temperature conditions, securing dead air spaces or pockets as distinguished from intended passages, and trapping the air as distinguished from providing for fluid flow.

30 Further purposes will appear in the specification and in the claims.

I have preferred to illustrate my invention by but three forms thereof, selecting forms which are practical, efficient and 35 quite inexpensive, and which at the same time well illustrate the principles of my invention.

Figure 1 is a broken, longitudinal side elevation of a rotary kiln illustrative of one 40 general type of apparatus with which my invention is useful.

Figs. 2 and 4 are cross-sections of a structure such as that shown in Fig. 1, showing two forms of my invention.

45 Figs. 3 and 5 are perspective views of fire bricks, such as are shown in Figs. 2 and 4 respectively.

Fig. 6 shows in perspective a third form of brick.

50 In the drawing similar numerals indicate like parts.

In accordance with the requirements of the statute I have illustrated my invention in connection with one piece of apparatus,

a rotary kiln, but recognize that it is useful generally for the purpose of lining any metal casing with fire brick in which the faces of heated fire brick would come in contact with the surface of the casing.

In the rotary kiln structure illustrated 60 in Fig. 1, it is necessary to use an outer metallic casing or cover 6, in order to secure the strength required. This casing must be lined throughout its length, in order to stand the heat. It is supported at intervals by rings 7 and coöperating bearing structure shown at 8, of which supports two only are shown in the illustration; and is rotated from any suitable shaft 9 by means of gears 10, 11, shaft 12, and gears 13, 14, 15 70 and 16, all well known in the art.

Because of the high temperature attained, the entire interior brick surface 17 becomes highly heated, and the bricks as ordinarily used have transmitted this heat through 75 substantially the entire outer surface of the brick to the adjoining and engaging interior surface 18 of the cylinder. A proposal by Wentz (U. S. Patent 714,843, Dec. 2, 1902) providing longitudinal channels between 80 the brick and the casing, was objectionable because the channels are much too long to obtain any appreciable benefit from the entering air, which becomes heated very quickly, and because the circulation provided greatly increases the convection heat 85 transfer from the brick to the metal.

I aim to reduce the area of brick contact with the cylinder while avoiding circulation by providing pockets or segregated air 90 spaces of dead air.

These need not be deep in a radial direction to secure effective heat insulation and are best made shallow to retain as much of the strength of the full-bodied brick as 95 possible and to reduce breakage of the flanges. They may be used in otherwise solid brick as in Figs. 3 and 5, or in hollow tile as in Fig. 6.

In order to prevent longitudinal movement of the air through any extended distance, I provide my contact primarily by means of the faces 19, 19' of circumferentially extending ribs 20, 20'.

For some purposes it will not be objectionable to allow the air space at 21 to extend throughout the circumference of the lining as in Fig. 2, and as is provided for by

the ends of the space 21 open at 22 as in Fig. 3. However, for more complete deadening of the air space and more complete segregation of the several air spaces into 5 heat-insulating air pockets, it is desirable to provide flanges 23 whose edges 24, 24' engage with the metal of the surrounding casing. This gives a more effective dead air 10 space, shown as one pocket in Fig. 5 and as 15 divided into two pockets in Fig. 6. The additional surface of contact 24 with that at 19 provides but a very slight total area for conduction of heat to the surrounding metal.

15 It will be evident that the longitudinal interruption of the air space by flanges to secure dead-air pockets, and the small contact surfaces are quite desirable and may be applied to various arts and in various 20 specific forms, all of which will come within the spirit and scope of my invention.

Having thus described my invention, what I claim as new and desire to secure by Letters Patent is:—

1. In an iron-incased brick lined, calcining chamber or furnace, the novelty which consists in wedge shaped bricks having the area of contact between the lining brick and the inclosing casing reduced to flanges only, the 30 structure being sealed against passage of gases longitudinally of the casing and the bricks being held in position by their mutual wedging actions.

2. In a structure of the character set forth 35 in claim 1, the novelty which comprises longitudinally extending flanges in connection with transverse flanges, so that transverse air movement will be interrupted by the longitudinally extending flanges.

40 3. In a structure of the character set forth in claim 1, the novelty which comprises a lining freed from passages for air from the

interior to the casing by the lateral contact of the bricks.

4. In a structure of the character set forth 45 in claim 2, the novelty which comprises a lining freed from passages for air from the interior to the casing by the lateral contact of the bricks.

5. The combination of a metallic casing 50 or shell of a calcining chamber or furnace and lining bricks of wedge shape, having the outer ends of the bricks flanged and larger than the inner ends thereof, providing flange contact between the bricks and the 55 casing with intermediate dead air space, the flanges preventing passage of the air axially with respect to the casing.

6. The combination of a metallic casing of a calcining chamber or furnace and lining 60 brick therefor, having the outer ends of the bricks larger and providing flange contact between the bricks and the casing with intermediate dead air spaces, the flanges extending both circumferentially and axially 65 of the casing to shut off both axial and circumferential air passage through the spaces.

7. The combination of a metallic casing of a calcining chamber or furnace and lining bricks therefor, forming air spaces between the outer ends of the brick and the casing, to shut off from axial air movement therebetween and having the bricks in contact at their sides to shut off air movement therethrough.

75 8. The combination of a metallic casing of a calcining chamber or furnace and lining bricks therefor, having flanges at their outer ends in contact with the casing and with the flanges of adjoining bricks, to provide dead air spaces therebetween, the bricks being held in place by each other.

SIMON HENRY HARRISON.
